(57)

CLAIM

The ornamental design for a prosthetic, as shown and described.

DESCRIPTION

1.-2. Prosthetic

1.1 : Perspective

1.2 : Front

1.3 : Back

1.4 : Top

1.5 : Bottom

1.6 : Right

1.7 : Left

2.1 : Perspective

2.2 : Front

2.3 : Back

2.4 : Top

2.5 : Bottom

2.6 : Right

2.7 : Left

1 Claim, 14 Drawing Sheets(56)
